UNITED STATES PATENT OFFICE

100,263

DESIGN FOR A SUGAR BOWL

Alfred F. Fukal, Chicago, Ill., assignor to Chicago
Flexible Shaft Company, Chicago, Ill., a corporation of Illinois

Application April 9, 1936, Serial No. 62,026

Term of patent 3½ years

To all whom it may concern:

Be it known that I, Alfred F. Fukal, a citizen of the United States, residing at Chicago, in the county of Cook and State of Illinois, have invented a new, original, and ornamental Design for a Sugar Bowl, of which the following is a specification, reference being had to the accompanying drawing, forming part thereof.

In the drawing:

Figures 2 and 3 are side views thereof taken at right angles with each other.

I claim:

The ornamental design for a sugar bowl substantially as shown.

ALFRED F. FUKAL.
